Le Roy W. Hardell, Chicago, Ill., assignor to Stewart-Warner Corporation, Chicago, Ill., a corporation of Virginia

Application September 21, 1946, Serial No. 133,477

Term of patent 14 years

(Cl. D56—4)

To all whom it may concern:

Be it known that I, Le Roy W. Hardell, a citizen of the United States, residing in Chicago, in the county of Cook and State of Illinois, have invented a new, original, and ornamental Design for a Radio and Phonograph Cabinet, of which the following is a specification, reference being had to the accompanying drawing, forming part thereof.

Fig. 1 is a front perspective view of a radio cabinet showing the design of the present invention;

Fig. 2 is a front view thereof;

Fig. 3 is a back view thereof; and

Fig. 4 is a view of the left end. The view of the right end is the reverse complement of the view shown in Fig. 4.

I claim:

The ornamental design for a radio and phonograph cabinet, substantially as shown and described.

LE ROY W. HARDELL.
